UNITED STATES PATENT OFFICE.

MARTIN V. TEETOR, OF ROCHESTER, NEW YORK.

CLOTHESLINE HANGER.

1,405,073.

Specification of Letters Patent. Patented Jan. 31, 1922.

Application filed December 29, 1920. Serial No. 433,762.

To all whom it may concern:

Be it known that I, MARTIN V. TEETOR, a citizen of the United States, residing at Rochester, in the county of Monroe and State of New York, have invented certain new and useful Improvements in Clothesline Hangers; and I do declare the following to be a full, clear, and exact description of the same, taken in connection with the accompanying drawings, forming a part of this specification.

My invention relates to clothes line hangers of the kind used for hanging a line on which clothes may be hung up to dry, and which are often suspended at considerable heights and the line pulled around so that the clothes may be secured thereto and removed therefrom from one end of the loop. The principal object of my invention is to provide an improved device of this kind, which is simple in construction, and which permits the full use of both elements of the loop without danger of dislodging the clothes or the means by which they are secured to the line. A further object of my invention is to produce a hanger of this kind having a plurality of hooks successively engaged by the line and movable to lift and carry the clothes suspended from the line past the hanger. More specifically, the object of my invention is to provide a hanger of this kind, which is revoluble about an axis and which is provided with a plurality of movable arms having hooks on which an endless clothes line may be suspended, and outwardly projecting portions adapted to lift and carry articles suspended from the line in the vicinity of the hanger. To these and other ends my invention resides in certain arrangement and combination of parts, illustrated in the accompanying drawing and particularly pointed out in the appended claims.

In the drawings:

Figure 1 is a plan view of my improved clothes line hanger, showing an endless clothes line suspended therefrom and

Figure 2 is a sectional elevation of the same, showing the bracket on which it is mounted.

Similar reference numerals refer to the same parts in all the figures of the drawings.

In the drawings, 1 is a bracket having a flanged base member by which it may be secured to any suitable vertical support by

screws or other suitable means. The bracket 55 1 has a horizontally extending arm 2 bent downwardly, as at 3, at its outer end where it is provided with a suitable bearing on which my improved hanger is revolubly supported. 60

My improved hanger comprises a hub 4 having a central bearing opening by which it is revolubly supported on the arm 3 of the bracket 1. A nut and washer or any other suitable means may be employed for supporting the hub 4 on its bearing. The hub 4 has a plurality of radially extending arms 5, each of which may be provided with a downwardly and outwardly extending finger 6 at its outer end. Pivotaly mounted on each of 70 said arms is a movable member or arm 7. Each of the arms 7 has a pair of perforated projecting ears 8 which engage and turn on pins 9 fixed in the arms 5, and normally rest on the fingers 6 in a downwardly and outwardly inclined position. The inner ends of the movable arms are each formed with an upturned portion forming a hook 10, which hooks are adapted to engage and support one end of an endless cord or clothes line 11. 75 In practice, it will be understood that two hangers are employed and the cord is looped about both on which it is supported to travel in each direction turning the hangers, and successively engaging the hooks 10 and 80 swinging the arms 7 from the inclined position shown in the right of said figure. During this movement of the arms 7 from the inclined to the horizontal position the lower outer ends 12 of the arms engage the clothes 85 or other articles suspended on the line and carry them past the hanger until the line again disengages the hook 10 and the arm 7 drops to normal position under the influence of gravity. 90

In order to prevent the arms 12 from catching the clothes and failing to release them when the hooks 10 are released from the line or from tearing delicate fabrics, I provide the ends thereof with yokes or bows 13 in 100 the form of bows having inturned ends which cannot catch or tear the clothes engaged thereby.

When the arms 7 engage the line it will be noted that they move to raise the clothes and at the same time carry them outward away from the hub. The weight of the clothes also pulls the hooks 10 against the line engaged 105

thereby and tends to automatically maintain the line taut and prevents it from being accidentally displaced.

Having described my invention, what I claim and desire to secure by Letters Patent is:

1. A clothes line hanger, comprising a hub adapted to revolve about a vertical axis, a plurality of arms projecting therefrom, a movable arm pivoted intermediate its ends to the outer end of each of said first named arms, and means on said movable arms for engaging a clothes line.

2. A clothes line hanger, comprising a revoluble hub, a plurality of arms projecting therefrom, a movable arm pivoted to the end of each of said first named arms, devices on said movable arms for engaging clothes and hooks also provided on said arms for engaging a clothes line whereby they are moved to engage the clothes.

3. A clothes line hanger, comprising a hub adapted to revolve about a vertical axis, a

plurality of arms projecting therefrom, having downwardly inclined fingers on their outer ends, a movable arm pivoted to the outer end of each of said first named arms and normally supported in an inclined position on said fingers, and means on said arms for engaging a clothes line whereby said arms are moved to a horizontal position.

4. A clothes line hanger, comprising a hub adapted to revolve about a vertical axis, a plurality of arms projecting therefrom, having downwardly inclined fingers on their outer ends, a movable arm pivoted to the outer end of each of said first named arms and normally supported in an inclined position on said fingers, means on said arms for engaging a clothes line whereby said arms are moved to a horizontal position to lift and carry articles suspended from the line, and bows on the outer ends of said arms for engaging the clothes.

MARTIN V. TEETOR.
